UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,066, dated September 9, 1902.

Application filed July 29, 1902. Serial No. 117,585. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is illustrated in front view.

The leading feature of my design consists of a frame, the sides of which have plain outer and inner edges, the cross-piece at the top having a plain upper edge. The side pieces are ornamented at the bottoms by urn-like diversified scrollwork, and at the tops are shield-like portions bearing heads. Suspended from the shields are two crossed cornucopias. The cross-piece is in the shape of a

hood bearing diversified scroll and foliation work. The center or summer front has a border-line near its outer edge entwined with grape-vine foliage and depicts a winter landscape scene with the figures of Cupid and a 25 woman in the foreground kneeling beside an open fire. Below the summer front and extending between the side pieces is an open-work frame.

I claim—

The ornamental design for a fireplace-front as herein described and shown.

In testimony whereof I have hereunto set my hand in the presence of two subscribing witnesses.

THOMAS M. DUDGEON.
